UNITED STATES PATENT OFFICE.

GEORGE STEPHENS, JR., OF DANVERS, ILLINOIS.

HOG-SUSPENDING DEVICE.

1,017,185.

Specification of Letters Patent.

Patented Feb. 13, 1912.

Application filed April 27, 1911. Serial No. 623,635.

To all whom it may concern:

Be it known that I, GEORGE STEPHENS, Jr., a citizen of the United States, residing at Danvers, in the county of McLean and State 5 of Illinois, have invented certain new and useful Improvements in Hog-Suspending Devices, of which the following is a specification.

This invention relates to a device for the 10 use of farmers, small butchers, etc., in slaughtering and suspending hogs, the object of the invention being to provide a simple, convenient and inexpensive device of this character upon which the hogs may be 15 slaughtered and thereafter readily and conveniently suspended.

A further object of the invention is to provide a device of this character which may be readily and conveniently transported 20 from place to place.

The invention consists of the features of construction, combination and arrangement of parts hereinafter fully described and claimed, reference being had to the accompanying drawings, in which:

Figure 1 is a perspective view of a suspending device embodying my invention, showing the front platform lowered for use. Fig. 2 is a similar view showing the front 30 platform elevated for the convenient transportation of the machine. Fig. 3 is a sectional plan view of the device. Fig. 4 is a vertical longitudinal section thereof.

Referring to the drawings, 1 designates an 35 elevated main platform supported upon front and rear cross bars 2 and 3 secured to four corner posts 4, which posts extend below said platform and are secured to sills or runners 5, on which the device may be 40 drawn from place to place. The front ends of the sills carry clevises 6, to which a suitable draft device may be secured for the attachment of draft animals. The corner posts 4 extend upwardly in convergent relation to a suitable elevation above the platform 1 and are connected at their upper ends by longitudinal bars 7 and cross bars 8, forming a rectangular head frame, the parts being bolted or otherwise securely fastened 45 together. The rear ends of the bars 7 and the opposite ends of the bars 8 respectively project beyond the rear end and sides of the frame to form a series of suspending arms 9, reinforced from the posts by braces 10. Six

outwardly projecting suspending arms are 55 thus provided around the head frame, the front ends of the bars 7 terminating flush with the front face of the front cross bar 8.

Hinged or pivoted to the front of the platform 1 is a front platform 11 adapted to be 60 swung downward to a position in horizontal alinement with said platform 1 and to be supported in such position by pivoted folding legs 12. On this platform 11 the hogs are slaughtered. When the device is not 65 in use for slaughtering purposes or is in storage or process of transportation, the platform 11 is swung or folded upward against the head frame and may be secured by any suitable fastening, such as a hook 13 70 on the head frame adapted to engage an eye 14 on said platform. When the front platform is thus folded the machine may be conveniently transported or stored in close compass.

75 A derrick, comprising a mast 15 provided with a horizontal arm 16 reinforced from the mast by a brace 17, is provided for lifting and swinging the hogs around the appliance so that they may be suspended from 80 the arms 9. The mast is journaled in a bearing on the platform 1 and a bearing carried by longitudinal pieces 18 and a cross piece 19 fastened to the head frame and carries at its lower end a windlass 20 of any 85 ordinary construction. To this windlass is connected one end of a chain or cable which passes upwardly alongside the mast, thence over a pulley 21 at the top of the mast and thence forwardly over the arm 16 and has 90 its free end suspended from a pulley at the free end of the arm 16 and provided with a hook 23 for the attachment of a sling 24 which is adapted for connection with a gambrel applied to the body of the hog to be 95 suspended. After each hog is slaughtered, a gambrel is applied thereto, the sling connected therewith and the windlass operated to elevate the hog, after which the crane is turned to bring the hog into proximity to 100 the desired suspending arm 9, the gambrel being detached from the sling and slid onto the arm 9 while the hog hangs suspended. In this manner the hogs may be conveniently suspended around and from the head frame 105 with a minimum amount of time and labor on the part of the operator.

The advantages of the device will be read-

ily understood from the foregoing description and its convenience to farmers and small butchers appreciated.

Having thus described the invention, what

5 I claim is:

A hog suspending device comprising a frame including upwardly converging corner posts or uprights, a platform arranged between and carried by said uprights, said 10 platform being provided with a bearing, longitudinal and transverse bars mounted upon the uprights above the platform and extended to form a series of projecting arms at the sides and rear of the device, a bearing

supported by said bars in alinement with the 15 platform bearing, a crane journaled in said bearings and having its arm projecting laterally beyond the vertical plane of the bars, and suspending means carried by the crane and arranged to be moved into proximity 20 to said suspending arms by the rotation of the crane.

In testimony whereof I affix my signature in presence of two witnesses.

GEORGE STEPHENS, JR.

Witnesses:

WALKER R. FLINT,
W. R. CLICKENER.
